UNITED STATES PATENT OFFICE.

HENRY F. SAWTELLE, OF LEOMINSTER, MASSACHUSETTS.

UMBRELLA.

SPECIFICATION forming part of Letters Patent No. 313,111, dated March 3, 1885.

Application filed January 18, 1884. (No model.)

To all whom it may concern:

Be it known that I, HENRY F. SAWTELLE, a citizen of the United States, residing at Leominster, in the county of Worcester and State 5 of Massachusetts, have invented certain new and useful Improvements in Umbrellas; and I do hereby declare that the same are fully described in the following specification, and illustrated in the accompanying drawings.

This invention relates to improvements in umbrellas; and it is particularly adapted for such purpose, although the invention, with a slight modification as to size and minor details, may be equally useful for parasols, and 15 as portable shades or tents for the use of artists when sketching or painting outdoors, or for similar purposes.

The invention is so constructed that when not in use the ribs, stays, and cover of the 20 umbrella can be folded together and inclosed within the hollow stick, having thus the appearance of an ordinary stout walking-cane, and may then be used for such a purpose, and at the same time the cover, stays, and 25 ribs of the umbrella are fully protected from injury and wear.

The invention is carried out as follows, reference being had to the accompanying drawings, where Figure 1 represents a side elevation of the invention when the umbrella is 30 inclosed within its hollow stick. Fig. 2 represents a longitudinal section of the same on the line A B shown in Fig. 1. Fig. 3 represents a central longitudinal section of the 35 invention when expanded for use as an umbrella. Fig. 4 represents a plan view of the duplex joints at the inner ends of the ribs. Fig. 5 represents a sectional elevation on the line C D shown in Fig. 4. Fig. 6 represents 40 a detailed side elevation of the sliding ferrule that is made detachable from the lower ends of the stays, and Fig. 7 represents an enlarged cross section on the line E F shown in Fig. 3, and showing the flexible connecting device between the lower ends of the stays 45 and the detachable ferrule.

Similar letters refer to similar parts wherever they occur on the different parts of the drawings.

50 a represents the umbrella stick or handle, made hollow, as shown in Figs. 2 and 3, so as to serve as a case or receptacle for the folded

cover, ribs, and stays, as shown in Figs. 1 and 2, when the invention is not required for use as an umbrella. The upper end of hollow 55 metal stick or handle a has secured to its inner end a plug, a', having a central screw-threaded spindle, a'', projecting from it, adapted to pass through the central perforation, b', of the ring b, to which the inner ends of the 60 ribs c c are jointed, as shown in Fig. 3.

a³ is a detachable point, made with a central internal screw-thread at its base, and adapted to be screwed over the screw-threaded spindle a'', as shown in Fig. 3, to hold the ring b 65 and inner portion of the cover d and its ribs c c in proper position while the umbrella is in use open or closed, as the case may be. After the cover has been detached from the handle and inclosed within the hollow handle a, 70 the point a³ is screwed onto the spindle a'', as shown in Figs. 1 and 2. The ring b is not hinged directly to the inner ends of ribs c c, as is usual on ordinary umbrellas or parasols, for to enable the cover and ribs and stays e e 75 to be folded together in the smallest space possible I find it necessary to hinge the inner end of each rib c to an intermediate duplex joint, c', each of such pieces being hinged in its inner end to the ring b, and in its outer 80 end to the inner end of one of the ribs c, as shown in detail in Figs. 4 and 5.

e e represent the stays, hinged in their outer ends to the respective ribs c c in any of the usual ways, and in their inner ends to an elastic joint or ring composed in part of chains c' e', and in part of flexible springs e'' e'', or in any other or equivalent elastic, expansive, or yielding manner, to produce an elastic ring or joint at this place, so as to permit said elastic 85 ring to be pushed over the upper end of ferrule f, and to rest in the annular groove f', (shown in Figs. 6 and 7,) thereon when the umbrella is in use, and to be easily detached from said ferrule when not desired for use 90 and preparatory to folding it within the hollow stick a.

g is a catch or locking spring hinged in its upper end at c'' to one of the duplex joints c', as shown in Fig. 5, and provided in its upper 100 end with an inwardly-projecting lip, g', adapted to be confined between the upper end of stick a and under side of ring b when the umbrella is in use, so as to prevent said locking-

spring g from swinging away from stick a when in such use. The lower end of spring-catch g has a locking-notch, g'' , as shown in Figs. 3 and 6, so as to lock on the inside of ferrule f and keep the cover of the umbrella in an expanded position while in use, as shown in said Fig. 3. The ferrule f is provided in its lower end with a number of notches, $f'' f''$, (shown in Figs. 3 and 6,) to engage with the locking projection g^3 in the lower end of catch g , as shown in said Figs. 3 and 6.

h is a spring-catch riveted or otherwise secured to the handle a at h' , and having locking projections h'' and h^3 , extending outward through corresponding perforations in the shell a , as shown in Fig. 3. The upper locking projection, h'' , serves to hold the ferrule f down on the lower end of handle a when the umbrella is temporarily closed, and the lower projection, h^3 , serves to hold the said ferrule f in its lowest position on the handle a when said ferrule is detached from the elastic joint connected to lower ends of stays $e e$ and the cover of the umbrella is stowed away within handle a , as shown in Figs. 1 and 2.

i is a hollow knob or cap adapted to close the lower open end of stick a when the umbrella is used as shown in Fig. 3, as well as when it is folded together and inclosed within the hollow handle a , as shown in Figs. 1 and 2. The said knob or cap may be screwed on the end of handle a or made detachable from it by means of a spring-catch or other well-known or equivalent device to equal advantage.

When the umbrella is not required for use, the cover, ribs, and stays are folded together and inclosed within the hollow handle a , as shown in Fig. 2, and in this condition the handle a may be used as an ordinary walking-cane.

When the umbrella is desired for use, the cap i is removed from end of handle a , and the cover, ribs, and stays withdrawn from within the handle a . The point a^3 is then detached

from the upper end of handle a , and the latter pushed upward through the flexible ring $e' e''$ until the screw-threaded projection a^3 penetrates the perforation b' in the ring b , when the point a^3 is screwed on the projecting end of screw a'' , as shown in Fig. 3. The flexible ring $e' e''$ is then placed around the grooves f' on the ferrule f , and the latter is pushed up on the handle a until locked in position with spring-catch g for holding the umbrella open, as shown in Fig. 3. The cap i is then attached to open lower end of handle a , as shown in said Fig. 3.

Having thus fully described the nature, construction, and operation of my invention, I wish to secure by Letters Patent and claim—

1. In a folding umbrella, the cover d and ribs $c c$, in combination with ring b and intermediate duplex joints, $c' c'$, as and for the purposes set forth.

2. In a folding umbrella, the cover d , ribs $c c$, and stays $e e$, having their lower ends connected by means of an expansive joint, $e' e''$, in combination with the ferrule f and its annular groove f' , as and for the purpose set forth and described.

3. The hollow handle a and detachable cover d ; with its ribs $c c$, ring b , and duplex joints $c' c'$, stays $e e$, in combination with the flexible joint $e' e''$, connecting the lower ends of stays $e e$, the ferrule f , having annular groove f' , notches f'' , and the spring-locking device $g g' g'' g^3$, as and for the purpose set forth.

4. The hollow umbrella handle a , having yielding locking projections $h'' h^3$ near its lower end, in combination with the sliding ferrule f , as and for the purpose set forth.

In testimony whereof I have affixed my signature in presence of two witnesses.

HENRY F. SAWTELLE.
